UNITED STATES PATENT OFFICE.

JOHN H. FOX, OF NEW YORK, N. Y.

DESIGN FOR A BOTTLE-FILLING NOZZLE.

SPECIFICATION forming part of Design No. 34,782, dated July 16, 1901.

Application filed April 20, 1901. Serial No. 56,793. Term of patent 7 years.

To all whom it may concern:

Be it known that I, JOHN H. FOX, a citizen of the United States, residing at 234 East Thirty-third street, New York, county of New York, State of New York, have invented and produced a certain new and useful Design for a Bottle-Filling Nozzle, fully described and represented in the following specification and the accompanying drawings, forming a part ⁵ of the same.

The present design consists of a shape for a bottle-filling nozzle such as is connected with a draft-arm for the supply-pipe upon a bottle-filling apparatus.

¹⁵ In the drawings, Figure 1 is a side view of the nozzle, and Fig. 2 is a longitudinal section of the same.

The nozzle is formed with tube *a*, having at its upper end the conical enlargement or boss ²⁰ *b*, and above the boss the coupling *f*, knurled

upon the outer side. The tube *a* is closed at the bottom end *c* and provided with lateral perforations *d*, and the boss *b* has its small end connected with the said tube. The coupling *f* is formed internally with a screw-thread, as shown in Fig. 2, and a central bore *e* extends from the interior of the coupling to the perforations *d*. ²⁵

Having thus described my design, what I claim, and desire to secure by Letters Patent, ³⁰ is—

The design for a bottle-filling nozzle as herein shown and described.

In testimony whereof I have hereunto set my hand in the presence of two subscribing ³⁵ witnesses.

JOHN H. FOX.
